UNITED STATES PATENT OFFICE.

CARTER WILLIAMS, OF PHILADELPHIA, PENNSYLVANIA.

CANOPY-FRAME.

SPECIFICATION forming part of Letters Patent No. 468,280, dated February 2, 1892.

Application filed August 1, 1891. Serial No. 401,395. (No model.)

To all whom it may concern:

Be it known that I, CARTER WILLIAMS, a citizen of the United States of America, and a resident of Philadelphia, in the State of Pennsylvania, have invented and produced a new and useful Improvement in Canopy-Frames, of which the following is a specification, illustrated by the accompanying drawings, which form a part hereof and to which reference is had.

My invention relates to certain new and useful improvements in canopies or shelter-awnings for sidewalks, and is especially designed to be erected in the front of dwellings and places of entertainment in such manner as to extend from the curb of the sidewalk to the entrance of the building, whereby persons alighting from vehicles to the sidewalk may have a dry and sheltered entrance to the building, the canopy being constructed in such manner that the same shall be readily and quickly erected and disconnected and be capable of being packed within a small compass for easy transportation; and it consists in the novel construction and arrangement of parts hereinafter fully described, and afterward definitely pointed out in the claim, due reference being had to the accompanying drawings, forming a part of this specification, wherein—

Figure 1 is a perspective view showing the frame in position. Fig. 2 is a perspective view of the hood; and Fig. 3, a detail view of a portion of the forward or front pair of top rafters, illustrating the kerfs adapted to receive the clamps by means of which the hood is secured thereto.

Referring to said drawings, the letter A indicates four uprights or standards of rectangular shape in cross-section and of suitable length to raise the canopy to the proper height. The upper ends of each of said uprights are fitted in one member of a hollow elbow B, and in the other member of said elbows are fitted the lower ends of top rafters D, the meeting ends of said top rafters being fitted in hollow elbows E. The elbows B and E are each provided with a headed bolt C, which passes through suitable perforations in said elbows and corresponding perforations in the uprights and top rafters and is secured therein by means of thumb-nuts c.

F F indicate the side rails or braces, con-

sisting of wooden strips provided at each end with flat metallic plates f, provided with notches, which engage the headed ends of the bolts C. A similar rail F' extends from one apex of the top rafters D to the other and is secured to the elbows E in the same manner as the side rails F. The front or forward pair of top rafters D are each at or about their centers provided upon their upper and lower sides with grooves or kerfs d, for the purpose hereinafter described.

G indicates the hood, consisting of a rectangular frame g, divided longitudinally at its center and united by means of hinges g' g'. To each inner corner of said hood are secured vertically-depending braces g² g², from the lower end of each of which extend diagonal braces g³ g³, which at their upper ends are secured to the rear of said rectangular frame near the hinges, and additional diagonal braces g⁴ g⁴ extend from the depending braces g³ to the sides of the rectangular frame g. At or about the center of each of the diagonal braces g³ are secured by screws, bolts, or rivets clamps H, which are adapted to embrace the grooves d of the forward pair of top rafters D, and are secured therein by means of thumb-screws h. The frame thus constructed is designed to be covered by a canvas or other covering cut to fit the same, thus affording shelter from the curb to the entrance of a building, the hoods G protecting the exit from the vehicle.

Constructed as above described the entire frame can be readily and easily set up by inserting the standards and top rafters in the elbows, slipping the side rails and ridge-rail in place, and then tightening up the thumb-screws, after which the hood is clamped upon the outer pair of top rafters, as before described, and the canvas or other covering draped over the frame. In like manner the frame may be disconnected, the uprights, top rafters, side rails, and ridge-rail compactly bound together, and the hood folded over upon its hinges, and the whole wrapped up in or with the covering to form a compact package easily susceptible of transportation.

It will be readily understood that the uprights, top rafters, and ridge and side rails may be employed to form a series of frames, which, placed end to end, will co-operate to

form a canopy of any desired length, only one hood being necessary.

Having described my invention, what I claim is—

5 In a canopy of the class described, the combination, with the main frame comprising the uprights A, top rafters D, two of said top rafters being provided with kerfs d d, side rails F, and top rail F', of the hood G, consisting of a rectangular frame g, longitudinally divided and hinged at its center and provided at its

10 braces g^2 , the lower ends of which are connected to the frame g by inclined braces g^3 g^4 , and clamps H, secured to the braces g^3 and 15 provided with thumb-screws h, said clamps resting in the kerfs d d of the top rafters D and secured therein by said set-screws, substantially as shown and described.

CARTER WILLIAMS.
